[57] CLAIM

The ornamental design for a covered pitcher, as shown and described.

DESCRIPTION

FIG. 1 is a front elevational view of a covered pitcher showing my new design;

FIG. 2 is a right side elevational view thereof, the left side elevational view being a mirror image thereof;

FIG. 3 is a rear elevational view thereof; and

FIG. 4 is a top plan view thereof; the bottom of the covered pitcher being devoid of ornamentation.

Fig. 3

Fig. 4
